UNITED STATES PATENT OFFICE.

CHARLES S. RHOADS, JR., OF WEST LAFAYETTE, INDIANA, ASSIGNOR TO WESTERN ELECTRIC COMPANY, INCORPORATED, OF NEW YORK, N. Y., A CORPORATION OF NEW YORK.

SELECTOR.

1,244,544.

Patented Oct. 30, 1917.

Application filed February 18, 1916. Serial No. 79,033.

To all whom it may concern:

Be it known that I, CHARLES S. RHOADS, Jr., a citizen of the United States, residing at West Lafayette, in the county of Tippecanoe and State of Indiana, have invented a certain new and useful Improvement in Selectors, of which the following is a full, clear, concise, and exact description, reference being had to the accompanying drawings, forming a part of this specification.

This invention relates to selective signaling systems and is concerned more particularly with the production of a selecting device of use in systems of this or similar character.

One of the prime features of this invention is the production of an alternating current selector by which is meant one that may operate with positive and negative impulses, or reversals of current, which selector is of such a character that it is responsive to a code call, rather than to a call depending solely upon the number of impulses or alternations of current. The constructional features of the selector however are such that by a slight modification, for instance, it is available as a direct current selector, also of the code type, if desired.

This invention will be best understood by the explanation of one form of device constructed in accordance with it, which will now be described in connection with the accompanying drawings, in which—

Figure 1 is a front view of a selector in its normal starting position constructed in accordance with this invention;

Fig. 2 is a side view thereof;

Fig. 3 is a sectional view on line a—a of

Fig. 1;

Fig. 4 is a sectional view on line b—b of

Fig. 2;

Fig. 5 is a fragmentary view of a portion of the apparatus shown in Fig. 1, illustrating the pawl as engaging the teeth;

Fig. 6 is a fragmentary view similar to that of Fig. 5, the direction of the view taken being however that of Fig. 2;

Fig. 7 is a fragmentary view of a portion of the apparatus illustrated in Fig. 1 showing the contact arm as associated with the first stop arm;

Fig. 8 is a fragmentary view of Fig. 1 showing the contact arm in association with the second stop arm; and

Fig. 9 is a view similar to Fig. 1 of a form

slightly modified to illustrate its use as a direct current selector.

This improved selector may consist preferably of a base plate 1 upon which a permanent magnet 2 is mounted, this permanent magnet serving to support the entire structure, preferably because of its attachment to the heel piece 3. The heel piece serves an electromagnet having two coils 4, 5, which are used to operate the movable mechanism 6 of the selector. As shown the electromagnet coils 4 and 5 are remotely controlled by the diagrammatic representation of line wires 6 and 7, which line wires extend preferably to a central station at which a battery 8 divided into sections 8 and 9 is located, these sections being under the control of operating switches 10 and 11. It will be seen that if the switch 10 is operated a certain impulse is sent over the line wires, and if the switch 11 is operated an impulse of the reverse character is sent over the wires. In Figs. 1 to 9 inclusive the switches 10 and 11 are designed to be operated alternately.

The mechanism by which the switches 10 and 11 can be operated automatically and in such a way as to count the number of impulses has not been shown, since that forms no part of this invention and as such call boxes are parts of the prior art.

The magnet coils 4 and 5 have protruding pole pieces 12 and 13 upon which is supported a framework 14. This framework at its rear has a downwardly extending bracket 15 and at its forward extremity has a downwardly extending bracket 16, these brackets 15 and 16 serving as supports for an armature 17 of the device. The magnet coils also have inwardly projecting pole pieces 18 and 19, which inwardly projecting pole pieces 18 and 19, which co-operate with an armature 20. This armature 20 is pivoted upon brackets 21 which form rearwardly extending projections of the vertical arm 22. This vertical arm 22 is part of the framework 14 extending upwardly from the shelf 23 thereof. The framework 14 also has another upwardly extending arm 24 which together with the arm 22 serves as a support for the shaft 25 carrying the star or step-up wheel 26, which in case serves as the step-by-step element. The armature 20 is mounted upon a swinging rod 27, which as before stated is pivoted upon the arms 21, and this rod at its upper end carries a counterweight 28 so that the

normal position of this armature and arm is as shown in Fig. 2. The rod 27 further carries a finger 29 adapted to control the position of a pawl 30. This pawl is pivotally mounted upon the arm 22 at its upper extremity. Normally when the parts are in their neutral position as shown in Figs. 1 and 2, the finger 29 rests upon the tail piece of the pawl 30, thus holding it out of engagement with the star wheel 26. The rod 27 also carries a further finger 31 which is insulated from the said rod 27. The star wheel 26 may be provided with one or more projecting stop arms 32 and 33, preferably insulated from said star wheel, as shown.

The local circuit may then be completed, for instance, to the local signal 34, which with its battery 35 is included in a local circuit with the conductors 36 and 37 respectively connected to the fingers 31 and 33. A spring 38 normally tends to hold the star wheel in the position shown whereby the stop 39 provided upon the star wheel rests against the arm 24.

Now whenever the magnet coils 4 and 5 are energized, either with alternating current, positive or negative impulses, or direct current, then the armature 20 is attracted to its position between the pole pieces 18 and 19 and stays there, the armature 17 however being polarized through the agency of the permanent magnet 2 oscillates in accordance with the polarity of energization of the magnet coils 4 and 5.

Thus in the general operation of the device the first impulse, say of any given polarity, causes the armature 17 to occupy a position where it engages, say, the pole piece 12 at the same time that the armature 20 is attracted to its alternative position. An impulse of the reverse polarity will then reverse the position of the armature 17, but will retain the armature 20 in the same position it has just occupied.

The structure shown in Figs. 1 to 8 is designed for code ringing, although of course it may be used for straight impulses as will be readily apparent from the succeeding description. Supposing however that the device is used for code ringing purposes, the code to consist only of two digits, then but two arms 32 and 33 are necessary. With three digits three could be used, or other combinations effected. If but two digits are used, however, as shown in the figures, let it be assumed that the code signal of the device is 6-4, this being meant to signify that it takes six actuations of the star wheel 26 to bring the arm 32 directly beneath the finger 31 and that it takes four more actuations of this step-by-step element to bring the arm 33 directly beneath the pin or finger 31. If then six alternations are sent, the armature 17 carrying an escapement mechanism 50 actuates the star wheel 26 six times.

It must be remembered of course that the first impulse also caused an attraction of the armature 20, thus releasing the finger 29 from engagement with the pawl 30 and causing this pawl to enter the teeth of the star wheel 26. If after the six actuations a cessation of impulses occurs, then the armature 20 is released and it tilts back into the position of Fig. 2, whereupon the finger 31 rests in the notch provided at the extremity of the stop arm 32. It will of course be understood that only those star wheels 26 of those selectors are then held in their actuated position which have a stop arm 32 six steps removed from the neutral position. All of the other selectors are restored to normal because the rod 27 may continue all the way back into its neutral position to thus disengage the pawls 30 of those selectors and permit the springs 38 to return the star wheels thereafter to the neutral position. Then if the next number of the code is four, the sending of four additional alternations after the interval will again cause attraction of the armature 20 of those devices preferably held in position and will cause a step-by-step movement of the element 26 through four more steps to bring the arm 33 directly under the finger 31. A further cessation of impulses will cause the rod 27 of Fig. 2 to return clockwise or until the finger 31 engages the stop arm 33, thereupon closing the circuit through the local signal 34.

It must be understood of course that other instruments having the code 6-2, or 6-6, or whatever the case may be would not have their circuit closed as their second stop arms would not be under the finger 31. Thus in the case of these selectors which previously had been held in an actuated position, their star wheels 26 would also be returned to normal because the rod 27 would be permitted to make its complete return to normal to release the corresponding pawls 30.

It will be seen that due to the peculiar goose neck construction of the fingers 32 and 33 that the star wheels carrying them may be returned to normal even though these star wheels have carried said stop arms beyond the finger 31 because if the said stop arms are carried beyond the finger 31, then the corresponding rods 27 are restored entirely to normal so that the extremity of the finger 31 which would engage the stop arms if they were in a vertical position is below the goose neck portion so that there is no interference between the returning stop arms as their projecting goose necks pass back to normal over the fingers 31.

From this it is thought the operation of the code selector will be entirely clear. It may be pointed out that one impulse may be used for a restoring impulse as the digit 1 would not be used in the code. It will be

apparent then that under these conditions any previously selected star wheel would be returned to normal if one impulse is received by the magnet coils 4 and 5.

5 Referring more particularly to Fig. 9, it will be seen that the escapement 50 and the star wheel 26 have been replaced by a ratchet wheel 42 and a step up pawl 40, the armature 17 being held in a biasing position by 10 a spring 41. Under these conditions it will be seen that the device is capable of operation as a code selector for direct current systems, although of course alternating impulses could be used even with this style of 15 selector, the spring 41 however rendering one set of impulses innocuous.

From what has been described the nature of this invention will be readily clear to those skilled in the art.

20 What is claimed is—

1. A code device of the character described comprising a step-by-step element, actuating pawls therefor, electromagnetic means including two armatures responsive

25 to impulses of opposite polarity to actuate the pawls to advance said element, means controlled by said element and electromagnetic means and rendered operatively responsive thereby when said element is advanced into a predetermined position, and means controlled by said element and electromagnetic means to retain said element momentarily in a predetermined intermediate position when said element has been ad-

35 vanced into said intermediate position.

2. A code device of the character described comprising a step-by-step element, actuating pawls therefor, electromagnetic means including two armatures responsive

40 to impulses to actuate the pawls to advance said element, means controlled by said element and electromagnetic means and rendered operatively responsive thereby when said element is advanced into a pre-

45 determined position, and means controlled by said element and electromagnetic means to retain said element momentarily in a predetermined intermediate position when said element has been advanced into said inter-

50 mediate position.

3. A code device of the character described comprising a step-by-step element, actuating pawls therefor, electromagnetic means including two armatures responsive

55 to impulses of opposite polarity to actuate the pawls to advance said element, means controlled by said element and one of said armatures and rendered operatively responsive thereby when said element is ad-

60 vanced into a predetermined position, and means controlled by said element and said armature to retain said element momentarily in a predetermined intermediate position when said element has been advanced into

65 said intermediate position.

4. A code device of the character described comprising a step-by-step element, actuating pawls therefor, electromagnetic means including two armatures responsive to impulses to actuate the pawls to advance said element, means controlled by said element and one of said armatures and rendered operatively responsive thereby when said element is advanced into a predetermined position, and means controlled by 70 said element and said armature to retain said element momentarily in a predetermined intermediate position when said element has been advanced into said intermediate position.

5. A code device of the character described comprising a step-by-step element, actuating pawls therefor, electromagnetic means including two armatures responsive to impulses of opposite polarity to actuate the pawls to advance said element, means controlled by said element and one of said armatures and rendered operatively responsive thereby when said element is advanced into a predetermined position, said means including a finger on said armature and coöperating elements on said step-by-step element, and means controlled by said element and said armature to retain said element momentarily in a predetermined intermediate position when said element has been advanced into said intermediate position.

6. A code device of the character described comprising a step-by-step element, electromagnetic means including two armatures responsive to impulses to actuate said element, means controlled by said element and one of said armatures and rendered operatively responsive thereby when said element is actuated into a predetermined position, said means including a finger on said armature and a coöperating element on said step-by-step element, and means including the finger controlled by said element and said armature to retain said element momentarily in a predetermined intermediate position when said element has been actuated into said intermediate position.

7. A code device of the character described comprising a step-by-step element, electromagnetic means including two armatures responsive to impulses of opposite polarity to actuate said element, means controlled by said element and one of said armatures and rendered operatively responsive thereby when said element is actuated into a predetermined position, said means including a finger on said armature and a coöperating element on said step-by-step element, and means including the finger controlled by said element and said armature to retain said element momentarily in a predetermined intermediate position when said element has been actuated into said intermediate position.

- 5 diate position, said coöperating elements when alined with said finger coöperating therewith to hold said step-by-step element in position, said finger being out of the normal path of said coöperating elements when its associated armature is in either of its extreme positions.
8. A code device of the character described comprising a step-by-step element, 10 electromagnetic means including two armatures responsive to impulses to actuate said element, means controlled by said element and one of said armatures and rendered operatively responsive thereby when said ele- 15 ment is actuated into a predetermined position, said means including a finger on said armature and a coöperating element on said step-by-step element, and means including the finger controlled by said element and 20 said armature to retain said element momentarily in a predetermined intermediate position when said element has been actuated into said intermediate position, said co- 25 operating elements when alined with said finger coöperating therewith to hold said step-by-step element in position, said finger being out of the normal path of said coöperating elements when its associated armature is in either of its extreme positions.
9. A substation signal receiving device having a step-by-step element, actuating pawls therefor, electromagnetic means including two armatures responsive to impulses to actuate the pawls to advance the 30 element, a finger mounted upon one of the 35
- armatures, an arm mounted upon the step-by-step element, a signal controlling device rendered operatively responsive when the element has been advanced into a predetermined position with the finger and the arm 40 in engagement, and a second arm mounted upon the step-by-step element and coöperating with the finger when the element has been advanced to a predetermined intermediate position to hold the element in this in- 45 termediate position.
10. A substation signal receiving device having a step-by-step element, actuating pawls therefor, electromagnetic means including two armatures responsive to im- 50 pulses of opposite polarity to actuate the pawls to advance the element, a finger mounted upon one of the armatures, an arm mounted upon the step-by-step element, a signal controlling device rendered opera- 55 tively responsive when the element has been advanced into a predetermined position with the finger and the arm in engagement, and a second arm mounted upon the step-by-step element and coöperating with the finger 60 when the element has been advanced to a predetermined intermediate position to hold the element in this intermediate position.

In witness whereof, I hereunto subscribe my name this 31st day of January, A. D., 65 1916.

CHARLES S. RHOADS, JR.
